UNITED STATES PATENT OFFICE.

ANDREW RAPP, OF NEW YORK, N. Y.

FOLDABLE FURNITURE.

1,339,669.

Specification of Letters Patent. Patented May 11, 1920.

Application filed January 30, 1920. Serial No. 355,086.

To all whom it may concern:

Be it known that I, ANDREW RAPP, a citizen of the United States of America, residing at New York, in the county of New 5 York and State of New York, have invented certain new and useful Improvements in Foldable Furniture, of which the following is a specification.

The present invention relates to convertible furniture and has for its object to provide a construction whereby the furniture may be readily converted into a bed or combination desk and settee, such as used in schools, or folded together into the form 15 of a box or cabinet to occupy the least possible space.

With this object in view my invention consists in the novel construction, combination and arrangement of parts as will be 20 hereinafter more fully described and defined in the appended claims.

In the accompanying drawing which forms part of this specification and in which similar reference characters denote 25 corresponding parts, Figure 1 is a perspective view of the folded and contracted furniture; Fig. 2 a perspective view of the furniture extended to form a combination settee and desk; Fig. 3 a perspective view 30 of the unfolded and extended furniture forming a bed; Fig. 4 a vertical section on line 4—4 of Fig. 1; Fig. 5 a vertical section on line 5—5 of Fig. 3 and Fig. 6 a section on line 6—6 of Fig. 5.

Referring to the drawing more in detail 35 the furniture when entirely folded up and contracted has the appearance of a substantially rectangular box or cabinet *a*. The same is composed of a base portion *b*, sectional side walls *c*, *d*, *e* end walls *f* and *g* and a top *h*. The base *b*, side wall sections *c*, *d* and the end wall *g* are connected together to form a single unit, while the side wall sections *e* are connected together by a bottom piece or board *i* and with the end wall *f* to form another unit. These two 45 units are connected together to be extendible, so that when extended into the position shown in Fig. 2, the first named unit constitutes a desk and the second unit a settee or bench. The side walls *e* are extended 50 downwardly beyond the seat or board *i* to form legs for the settee and are formed near the lower edge on their outer faces with projecting longitudinal borders *e* of dove-tailed cross section adapted to slidably engage

correspondingly shaped grooves *b'* in the sides of the base portion *b*. The upper edges *e* of the sections *e* are cut out substantially in the form shown and are adapted when 60 the two units are contracted into the compact position of Fig. 1 to fit in and fill up the spaces *c* formed by correspondingly cut out portions of the side sections *c*, while the curved end edges *c'* and *d'* of the sections *c*, 65 *d* will bear against the curved edges of the upwardly extended rear parts *e* of the sections *e*.

The sections *d* to which the board or top *h* is fixed are pivotally attached to the sections 70 *c* by hinges *l* or the like fixed between the adjacent edges of the said sections and permitting the top to be tilted forwardly into the position shown in Fig. 3 when it is desired to convert the furniture into a bed. 75 The parts are so admeasured that the seat *i* of the settee will be even with the lower face of the board or top *h* when unfolded into the position shown in Fig. 3.

Extending between and fixed to the lower 80 reduced portions of the two side wall sections *c* is a shelf like sectional board *j*, *j'* the sections of which are hinged together as at *j* and adapted to fold flat upon one another, when the furniture is entirely folded 85 up and contracted or when extended into the form shown in Fig. 2, but which can be unfolded so as to overbridge the space between the seat *i* and the unfolded top *h* and to serve as a rest for a mattress. The sections 90 *j* are so admeasured and arranged that when unfolded they will fill the gap between the front edge of the seat *i* and the rear edge of the unfolded top *h* and will be even with the latter and the seat. 95

Pivots secured to the bottom face of the seat are horizontally tilting lateral arms *o* which are adapted when the furniture is converted into a bed to be swung out from underneath the seat and to extend parallel 100 to the side walls and serve as rests for the unfolded section *j*. The free ends *o'* of these arms *o* are hook shaped and adapted to engage grooves *c* in the side sections *c* of the desk unit to be thereby locked in unfolded 105 position.

The front end wall *g* is pivotally connected to the base by a hinge *k* or the like, so as to tilt forwardly, and permit the top *h* to be unfolded into the position shown 110 in Fig. 3 and serve as an auxiliary support therefor when in that position.

Locking hooks *p* and *r* are fixed to the sections *e* and *g* respectively and adapted when the parts are contracted into the form of a box, as shown in Fig. 1, to engage pins 5 *q* and *s* respectively to lock the parts in compact position.

The space between the top *h* and shelf like board *j*, *j'* may be utilized for storing a foldable mattress *n*, made to fit over the 10 extended and unfolded parts when constituting the bed, as indicated by dotted lines in Fig. 5.

The article thus constructed may be carried out in small size to serve as a toy.

15 What I claim is:

1. A convertible piece of furniture, composed of two separate units, of which one constitutes a desk and the other a settee, both said units being extendibly engaged 20 with one another to be capable of contraction and expansion, the top of the desk being tilttable so that in unfolded position it will be even with the seat of the settee and constitute with same a bed, and a foldable 25 shelf like member below the top adapted in unfolded position to overbridge the space between the seat and the unfolded top to complete the bed.

2. A convertible piece of furniture, composed of two units, of which one constitutes a desk and the other a settee, the latter having lateral extensions slidably engaging 30 the sides of the desk and permitting the settee to be extended or folded under the top of 35 the desk, the top of said desk being tilttable and adapted in unfolded position to lie even with the seat of the settee to serve with the latter as a bed and a foldable shelf

like member under the top of the desk adapted in unfolded position to overbridge the space between the extended seat and the top of the desk to complete the bed.

3. A convertible piece of furniture, consisting of a desk and settee slidably engaged with one another so as to be capable of being folded below one another when not in use, or expanded when in use, the top of said desk being tilttable so as to unfold forwardly to form an extension even with the seat of said settee, and in unfolded position to constitute with said seat a bed, a shelf like, foldable member under the top adapted in its unfolded position to overbridge the space between said seat and the unfolded top and complete the bed and means for locking the parts together in contracted and folded position.

4. A convertible article, consisting of a desk and a settee extendibly engaged with one another, the top of said desk being capable of tilting forwardly to extend evenly with the seat of the settee and constitute with the latter a bed, a member under the top of the desk serving as a shelf when the article is folded and as a rest part of the bed when the article is unfolded, means capable of engaging the desk when settee is extended to lock the latter in extended position and means for locking the parts in contracted and folded position.

In testimony whereof I affix my signature in presence of two witnesses.

ANDREW RAPP.
